UNITED STATES PATENT OFFICE.

JAMES A. DAVIS, OF WASHINGTON, DISTRICT OF COLUMBIA.

ANTISLIPPING HORSESHOE ATTACHMENT.

1,131,337.

Specification of Letters Patent.

Patented Mar. 9, 1915.

Application filed March 31, 1913. Serial No. 758,031.

To all whom it may concern:

Be it known that I, JAMES A. DAVIS, citizen of the United States, residing at Washington, District of Columbia, have invented 5 certain new and useful Improvements in Antislipping Horseshoe Attachments, of which the following is a specification.

This invention relates to devices adapted to be attached to horse shoes for the purpose 10 of providing means for preventing slipping of the shoe upon snow, ice and wet concrete.

The primary object of my invention is the provision of a very simple and effective attachment of the character stated which may 15 be easily applied to or removed from a horse shoe and wherein the calks may be readily applied to or removed from the attachment.

A further object of the invention is to provide means whereby the attachment may be 20 firmly supported by a toe clamp and heel clamps, and whereby the heel clamps may be laterally adjusted so as to conform to the peculiarities of any individual hoof.

A still further object is to so construct the 25 attachment that the distance between the toe calks and heel calks or between the toe clamp and the heel clamps may be adjustably varied to suit the shoe to different sizes of hoofs.

Another object of the invention is to so 30 construct the attachment that it may adapt itself to hoofs lacking in bilateral symmetry.

A further object is to provide calks having a plurality of cutting edges and so 35 mounted that each calk may be rotated to bring any one of the cutting edges into active position, and whereby the faces of the calk will be firmly supported to hold the calk against accidental rotary movement.

A still further object is to provide heel 40 clamping members adjustable with relation to the body of the attachment.

Other objects will appear in the course of the following description.

For a full understanding of the invention, 45 reference is to be had to the following description and accompanying drawings, in which:—

Figure 1 is an under side plan view of a 50 horse shoe attachment constructed in accordance with my invention; Fig. 2 is a side elevation of the attachment applied to a hoof; Fig. 3 is a perspective view of the toe clamp of the attachment shown in Fig. 1; Fig. 4 is an under side plan view of a

modified form of the attachment; Fig. 5 is a perspective view of a modified form of heel clamp with the attachment as shown in Fig. 4; Fig. 6 is a transverse section on the line 6—6 of Fig. 7; Fig. 7 is a transverse section on the line 7—7 of Fig. 6. Fig. 8 is a detail view of the tension bar shown in Fig. 4.

Corresponding and like parts are referred to in the following description and indicated in all the views of the accompanying drawings by the same reference characters.

The form of attachment illustrated in Figs. 1, 2 and 3 includes a front cross bar or plate designated 2. This plate at its 70 ends is bent upward as at 3 over the edge of the shoe, and then is connected to an ar- 75 cuate band 4 which fits over the toe of a hoof and forms a toe clamp whereby the forward end of the attachment is connected 75 rigidly to the shoe. The plate 2 at its op- 80 posite end is formed with downwardly ex- 85 tends, as illustrated in Figs. 6 and 7, the studs being screw-threaded and 90 designated 5, and being for the attachment 90 of the front calks 7. These front calks 7 are triangular in form so as to provide a plurality of flat sides 8 and cutting edges 9. Any one of the flat sides 8 is adapted to lie against and bear upon the plate 2 so that 85 any one of the points may be extended downward. When the calk is supported 90 against the front plate 2, it will be supported across its lower face so as to secure a thorough firm bearing.

Each face of the calk is formed with an aperture 10, these apertures or passages meeting centrally in the calk, as illustrated in Fig. 7. Passing through the stud 5 is a pin 11, this pin being preferably tapered, a 95 laterally extending opening for the passage of this pin being made through the calk. When the pin is forced through the calk and through the opening in the stud 5, the pin will act to clamp the calk rigidly to the 100 stud by a wedging action. The end of the pin is intended to be bent over as at 12, but when it is desired to readjust the calk, it is only necessary to bend up the end 12, re- 105 move the pin, and readjust the calk so as to bring another aperture 10 in co-incidence with the stud 5.

Attached to the plate 2 at its middle and extending rearward therefrom is a rod 13 which is screw-threaded. Extending trans- 110

versely across the rear portion of the shoe is a bar 14 formed with an elongated middle opening or passage 15. Extending through this passage is a rod 16 which is 5 screw-threaded and which is in alinement with the rod 13. Connecting the rods 13 and 16, and engaging the screw-threaded portions thereof, is a nut or turn buckle 17. It will be evident that the rods 13 and 16 10 must be screw-threaded in reverse directions, so that when the turn nut or buckle 17 is rotated in one direction, the rods 16 and 13 will be drawn together, and when rotated in the other direction, they will be forced apart. A set-nut 18 is also disposed 15 upon the rod 13 and adapted to engage with the turn buckle 17 to prevent any accidental rotation of the latter.

The rod 16 is formed at its ends with a 20 transverse tubular bore 19 interiorly screw-threaded at its ends for engagement with the screw-threaded shanks 20 of the heel engaging members 21. These members are 25 preferably formed integral with the shanks 22. Each member extends downward behind the heel of the horse shoe A and then forward so as to hook over the heel, as illustrated in Fig. 2. Each of these heel engaging members 21 is also formed with the forwardly projecting lug 23 which engages on the inside face of the heel as illustrated in 30 Fig. 1. It will be noted that these members 21 may be adjusted independently of each other and relative to the axial line of 35 the attachment, and that they may be rotated so that the lugs 23 of the members may have different angles with relation to the rod 16. Thus these heel engaging members may be accurately adjusted to fit any 40 peculiar form of shoe or to fit any peculiarities in the horse's hoof. It will further be observed that the members cannot move laterally by reason of the lugs 23, and that 45 they will lock behind the heels of the shoe A, and when locked they will be clamped rigidly in position.

The cross bar 14, as before stated, is provided with an elongated opening 15 in its middle for the passage of the rod 16. 50 Formed integral with the relatively large portions of this bar 14 are the laterally extending screw-threaded portions 24, these screw-threaded portions 24 extending at a slight angle to the middle portion of the bar 55 14. Screwed upon the ends of these screw-threaded portions 24 are the calks 25. These calks are triangular in form, as previously stated, so as to provide three bearing faces and three cutting edges, the bearing faces 60 being adapted to rest flat against the under face of the shoe immediately in front of the heel of the shoe. These calks have 65 interiorly screw-threaded apertures for the reception of the screw threaded portions 24 and they are held in adjusted position by

means of set-nuts 26. It will be seen that not only may the calks be laterally adjusted independently of each other and with relation to the axial line of the hoof or shoe, but that the bar 14 may be shifted laterally 70 with relation to the rod 16 so that the rod shall not pass through the middle of the bar 14, but to one side of the middle. This permits the shoe to fit hoofs in which there is no bilateral symmetry, and this is a very 75 important feature inasmuch as without this means of adjustment, an attachment which will fit the hoof of one horse will not fit the hoof of another. It will further be noted that the heel engaging members 21 may be 80 adjusted in correspondence with the adjustment of the calks 25. It will further be noted that after the calks 25 have been put in place and the toe and heel clamps tightened up, the rear portion of the attachment 85 may be drawn toward the forward portion of the attachment to tightly clamp the attachment upon a shoe by means of the turn buckle 17, and that this drawing together of the rods 13 and 16 does not affect the bar 90 14. This bar is held in adjusted position relative to the rod 16 by means of the set-nut 27 which engages the screw-threads of the rod 16 and which bears against the inner face of the bar 14. 95

The calks illustrated are adapted to be rotated so as to present fresh sharp edges to the pavement, and thus the same calks may be used for a considerable length of time without grinding. It may be particularly 100 noticed that the calks have a large flat bearing area of a size equal to the base of the triangle forming the calk, and that thus the calks are rigidly supported beneath the whole area and cannot get out of position. 105 The calks will not bend, they will not break, and when they become dull it is only necessary to readjust the calks to secure a new cutting edge until all three of the cutting edges have been worn out to an extent requiring a new calk entirely. This new calk, 110 of course, may be readily attached at any time.

In Figs. 4 and 5, I have shown another form of my construction, similar in its broad 115 features to the construction shown in Figs. 1 and 2. In this construction, however, the position of the rear calks may be adjusted relatively to the heel of the shoe and independently of the tension rod which is not 120 possible in the construction illustrated in Figs. 1 and 2. This adjustment is secured by the provision of links connecting with and engaging over the heels of the shoe. In Fig. 4, B designates the horse shoe and 26 125 designates a relatively small plate folded upon itself as indicated in Fig. 8. Pivoted to this plate by means of bolts 27, and extending radially outward from these bolts, 130 are the shanks 28 of hooks 29 which engage

over the toe of the shoe and form toe clamps. These hooks 29 are reduced each at its middle portion, as at 30, and rotatably mounted upon the reduced portions of the hooks or 5 toe clamps are the triangular calks 31 constructed in the same manner as the calks 25 previously described. The bases of these 10 calks rest solidly against the under side of the shoe, and the calks are held from any lateral movement by the fact that they are disposed upon the reduced portion of the shank 28. In the construction of this hook, the portion which forms the hook proper is reduced and inserted in an opening in the 15 extremity of the portion 28, this inner reduced end being pinned to the portion 28. By driving out the pin, the outer section of the shank may be removed from the inner section, and thus the calk removed and 20 replaced. The plate 26 is extended rearward in the form of a rod 32, the rear end of which is screw-threaded as at 33 and provided with a set-nut 34. The transverse bar 35 is constructed in the same manner as the 25 bar 14, and is formed with the laterally extending angular shanks 36. Threaded on these shanks are the calks 37 which are constructed in the same manner as the calks 35. Disposed between the calks 37 and set- 30 nuts 38 mounted on the shanks 36 are the rearwardly extending heel clamping links 39, one of which is shown in Fig. 5. These links comprise essentially a loop portion 40, preferably divided by transverse bars 41 to 35 provide a plurality of openings 42, the rear of the loop being extended rearward, then laterally turned, as at 43, and then upwardly bent and forwardly curved as at 44. The 40 inside edge of the shce, while the hook portion extends over the heel and clamps over the same. The shanks 36 of the bar 35 extend through any one of the openings 42 of the loop 40, and thus the rear calks 37 45 may be adjusted to any one of three separate positions, either immediately against the heel, near the middle of the shoe, as illustrated in Fig. 4, or at an intermediate point, and, at the same time, the heel clamping 50 hooks 39 may be drawn tightly into locking engagement with the heel of the shoe by turning up on the nut 34. The portion 35 is transversely slotted, as previously described for the bar 14, so as to permit the 55 heel clamps and heel calks to be adjusted on shoes where the cusps of the shoe are at varying distances from the axial center of the shoe. This form of shoe is used in the same manner as the shoe previously described. It may be readily adjusted, removed or replaced. It has this advantage 60 over the shoe first described, that the pivoted links or shanks 28 permit the toe clamping members to be adjusted near to or farther 65 from each other to fit any particular form

of hoof. It is further to be noted with regard to both of these shoes that the attachment never acts to spread the heel of the shoe, nor draw the cusps of the shoe together, but when once adjusted it holds the 70 shoe from lateral displacement and reinforces the hoof against shock.

In order to prevent snow or mud from balling up within the hoof, I preferably use in connection with the horseshoe attachment 75 a shield designated 45 and illustrated in Figs. 1 and 2. This shield may be made of thin sheet metal or any suitable material of like character and is provided upon its upper face with inwardly projecting lugs 46 80 through which the rods 13 and 16 extend, or if the shield is used with the construction shown in Fig. 4 through which the rod 32 extends. A shield of this character is particularly necessary inasmuch as the mechanism of the attachment is liable to collect 85 snow and mud. This shield is further of value in that it protects the tender portion of the horse's hoof, and also permits the hoof to be packed with cotton waste or like 90 material whereby medicaments may be applied directly to the hoof as is often necessary.

Having thus described the invention what is claimed as new is:—

95

1. A horseshoe attachment of the character described, including a toe clamp, oppositely disposed heel clamps, means for drawing the heel clamps toward the toe clamp, and means for laterally adjusting the heel 100 clamps with relation to the means for drawing the heel clamps toward the toe clamp.

2. A horseshoe attachment of the character described, including toe clamps, heel clamps, toe calks and heel calks, means for 105 drawing the heel clamps toward the toe clamps, and means for laterally adjusting the heel calks and the heel clamps independently of each other.

3. A horseshoe attachment of the character described, including a toe clamp, heel clamps, toe calks and heel calks, means for drawing the heel clamps toward the toe clamps, means for laterally adjusting the heel clamps and means for laterally adjusting the heel calks independently of the heel 115 clamps.

4. A horseshoe attachment of the character described, including a toe clamp, heel clamps, a longitudinally disposed tensioning 120 member operatively connected at its ends to the toe and heel clamps, means for longitudinally adjusting the heel clamps relative to the tensioning member, heel calks, and means for laterally and longitudinally adjusting the heel calks, independently of the heel clamps.

5. A horseshoe attachment of the character described, including a toe clamp, oppositely disposed heel clamps, a longitudinally 130

extending tightening member operatively connected to the toe and heel clamps, a calk supporting member, means operatively connecting the tightening member to the supporting member for longitudinal adjustment of the supporting member relative to the tightening member, said means permitting the lateral adjustment of the calk supporting member relative to the tightening member, 10 calks supported upon the supporting member, heel clamps operatively connected to the tightening member and longitudinally adjustable relative to the supporting member, and means for laterally adjusting the supporting members and the corresponding heel calks independently of each other.

6. A horseshoe attachment of the character described, including toe calks, heel clamps, a transverse member to which the heel calks are operatively connected, a tightening member engaging the transverse member to draw the heel calks toward the toe clamps, said transverse member being longitudinally adjustable upon the tightening member and laterally adjustable independently of and with relation thereto, and said heel clamps being provided with forwardly extending lugs engaging the inside faces of the shoe heels and operatively connected to 30 the tightening member.

7. A horseshoe attachment of the character described, including toe clamps, heel clamps, a tightening member connecting the toe and heel clamps, a heel calk carrying member, heel calks carried thereby, and

means for holding the heel calks in lateral adjustment upon the carrying member.

8. A horseshoe attachment of the character described, including a toe clamp, heel clamps, a tightening member, a transversely extending member through which the tightening member passes, said member having screw threaded laterally extending shanks, heel calks mounted upon said shanks, and means for holding the heel calks in any laterally adjusted position in the shanks.

9. A horseshoe attachment of the character described, including toe clamping devices, triangular toe calks adjustably mounted upon the toe clamp whereby the calks may be rotated to bring any one of the faces of the calks upward and the corresponding apex of the calk downward, a tension rod extending from said toe clamp, heel clamps operatively connected to the tension rod, a heel calk carrying bar having a slot through which the tension rod passes and having laterally extending annular screw threaded shanks, and triangular calks rotatably mounted upon the shanks whereby any one of the faces of the calk may be turned upward and the opposed apex of the calk extended downward.

In testimony whereof I affix my signature in presence of two witnesses.
